[57] CLAIM

The ornamental design for an adjustable colander for steaming food, as shown and described.

DESCRIPTION

FIG. 1 is a top plan view of an adjustable colander for steaming food showing my new design;

FIG. 2 is a front elevational view, the rear view being similar;

FIG. 3 is a bottom plan view;

FIG. 4 is a right side elevational view of FIG. 2;

FIG. 5 is a left side elevational view of FIG. 2;

FIG. 6 is a top plan view in a closed position with the handle having been removed and shown in front elevation; and

FIG. 7 is an enlarged fragmentary sectional view taken on line 7—7 of FIG. 3.
